UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,141,302.

Specification of Letters Patent.

Patented June 1, 1915.

Application filed October 6, 1911. Serial No. 653,117.

To all whom it may concern:

Be it known that I, ARTHUR BATES, a subject of the King of Great Britain, residing at Leicester, Leicestershire, England, have invented certain Improvements in Machines for Use in the Manufacture of Boots and Shoes, of which the following description, in connection with the accompanying drawings, is a specification, like reference characters on the drawings indicating like parts in the several figures.

The present invention relates to improvements in machines intended primarily for closing the channels and molding or bending the marginal portions of the soles of boots or shoes and in this respect the invention is in the nature of an improvement upon the machine which is described and illustrated in Letters Patent of the United States No. 1,019,085, dated March 5, 1912, issued upon a co-pending application filed by John Pennell Pride and the present applicant jointly. As in said prior machine, a machine embodying the present invention may also be provided with means for pounding the upper of the shoe adjacent the feather or upper face of the margin of the sole, the latter term being used in its generic sense to include not only the sole of the usual McKay, pegged or nailed shoe but also a double or tapped sole as well as the combined welt and outsole of a welt shoe. Preferably also means is provided for pounding the edge of the sole, thereby both assisting in the closing of the channel and improving the finish of the sole edge.

A principal object of the present invention is to simplify the construction and improve the operation of machines of the class described and with this object in view, a feature of the present invention comprises the provision of a work feeding wheel and a co-operating roll constructed and arranged to engage opposite sides of the margin of the sole together with mechanism for rotating both wheel and roll in the same direction, the relative speed of the roll being substantially, and preferably many times, greater than that of the wheel. With such a construction the sole engaging tools being

of suitable shape for the purpose will act not only to bend or mold the sole margin at a particular point but will also feed the shoe along so that the desired length of the sole margin will be progressively molded. At 55 the same time, the roll, which in the illustrated embodiment of the invention is provided with spiral ribs, acts to close the channel by laying or pressing down the channel flap. Preferably the wheel and roll are 60 frusto-conical in shape and are arranged on substantially horizontal axes with their bases oppositely directed so that during the operation of the machine the shoe may remain in substantially normal or upright position with the tread face of the sole resting upon and supported by the roll.

By providing, in addition to the tools which act upon the sole margin, a vibrating pounding tool acting upon the upper in the 70 crease, often termed the "welt crease," between the upper and the feather of the sole, the machine acts to "open up the welt" or to give the shoe a relatively "wide edge" as distinguished from a "close edge." That is 75 to say, the upper is pressed back from the edge of the sole at the same time that the sole margin is bent away from the upper so that the edge of the sole will appear to extend a relatively great distance beyond the 80 upper, which is often desired in certain classes of shoes, such as heavy McKay shoes.

These and other features of the invention will now be described in detail in connection with the accompanying drawings which 85 illustrate a preferred embodiment of the invention but it is to be understood that the invention may be embodied also in other specific forms without departing from the substance and scope of the invention as defined in the appended claims.

In the drawings: Figure 1 is a side elevation, partly in section, of the machine; Fig. 2 is a plan with a portion of the casing or machine frame and certain other parts cut 95 away to show the parts beneath; and Fig. 3 is a detail view of the edge beating tool and its actuating mechanism.

As illustrated, the machine comprises a base 2 having a vertically adjustable head 4 100

in the rear part of which is journaled transversely a driving shaft 6 and in the upper part of which is journaled longitudinally a sleeve 8 carrying at its front end a frusto-conical feed wheel 10, the sleeve being rotated from the driving shaft by means of a worm 12 and worm wheel 14. A swinging frame 16, bifurcated at its rear end and pivoted upon the shaft 6 provides bearings for a shaft 18 which is driven from the shaft 6 by bevel gears 20, 22. This shaft 18 at its front end has a frusto-conical roll 24 which is spirally ribbed to adapt it to close the channel since it is driven at a relatively high peripheral speed as compared with the peripheral speed of the feed wheel and with the rate at which the shoe is fed. The active elements of wheel 10 and roll 24 are substantially parallel but since the tread face 20 of the shoe is slightly rockered, or convex, in transverse section, the margin of the sole being operated upon is molded or bent away from the adjacent portion of the upper, thus opening up the crease between the upper 25 and sole, as above explained.

Upon the frame 16 near the roll 24 is pivoted on a short shaft 26 a vertically extending lever 28 which carries at its upper end a vibrating edge beating tool 30 having lateral ears 32 adapted to project under the sole. The tool 30 serves also as an edge gage and assists in maintaining the sole in proper cooperative relationship with the tools which act upon it. The shank of tool 35 30 may be adjusted in a socket in lever 28 and clamped by a bolt 34. Pivoted likewise on shaft 26 but at one side of lever 28, as shown in Figs. 2 and 3, is another lever 36 having a lug 38 at its rear side in a socket 40 of which is mounted a spring pressed pin 40 which bears against an abutment 41 upon lever 28. With this construction, motion imparted to lever 36 is transmitted yieldingly to lever 28 so that the tool 30 strikes 45 a yielding blow upon the edge of the sole and thus acts not only to solidify the edge but also, by reason of its tendency to upset the edge, assists the other tools in the closing of the channel. The mechanism for oscillating lever 36 comprises a rod 42 screwed into a pivoted block 43 at the lower end of lever 36, the other end of this rod being similarly connected to the lower end of a cam lever 44 which is pivoted to the machine frame at 45 and which carries a cam roll 46 that engages a face cam 48 on the driving shaft 6.

The machine is preferably provided also with an upper pounding tool 54 which is 60 located within and concentric with the feed wheel 10, its end projecting slightly beyond the end of the wheel. This pounding tool is attached to a spindle 56 which slides in the sleeve 8 and projects beyond it at the

rear of the machine. The end of this 65 spindle enters a recess 58 in a boss 60 at the upper end of the cam lever 44, above mentioned, and abuts against the end of a pin or screw 62 adjustably secured in the boss. To reduce wear the ends of the pin and of 70 the spindle may be case-hardened. To permit some play between the spindle 56 and the cam lever 44 but to prevent the entire withdrawal of the spindle from the recess, the boss 60 is provided with a transverse 75 hole 64 which receives a transverse pin 66 of smaller diameter extending through the spindle.

The front end of frame 16 and the roll 26 are normally supported in operative position by means of a plunger 70 movable vertically in a recess 72 in the head of the machine and bearing at its upper end against the frame 16. The plunger is pressed upwardly by a spring 74, the lower 80 end of which is supported by a hollow adjustable screw plug 76 but may be depressed by a suitable treadle (not shown) in a well-known manner in order that the work may be inserted between the feed wheel and the 85 channel closing roll. Adjustable or other stops 78, 80 upon the machine frame 4 and the swinging frame 16, respectively, limit the relative approach of roll and wheel.

It will be noted that the channel closing 90 roll 24 and the edge beating tool 30, being upon the same frame, always maintain the same relationship notwithstanding variations in the thickness of the work.

If any portion of the extreme edge of the 100 sole is very badly deformed or recessed away from the tread face, the lower surface of roll 24 may be used preliminarily to pound and reshape the sole edge. For this reason, a guard or rest 82 hung on pivot 105 shaft 26 may be provided. The pressure of the work against the tools 30, 54 may be relied upon to keep the cam roll 46 in operative relation to its cam or if desired a suitable spring acting upon lever 44 may 110 be employed for the purpose.

The operation of the machine in opening the crease, bending the sole margin and closing the channel will be readily understood from the foregoing description. As 115 indicated in Fig. 1, the shoe will be held by the operator in an upright position with its sole nearly horizontal. As the shoe is pressed inward against the pounding tools 30 and 54, while the margin of the sole is 120 gripped between the feed wheel 10 and the ribbed roll 24, not only will the channel be closed by the wiping action of the ribbed roll 24 but the margin of the sole will also be bent away from the upper and the upper 125 will be conformed to the last if, as indicated, the last is in the shoe.

Having now described my invention, what

I claim as new and desire to secure by Letters Patent of the United States is:—

1. A machine of the class described having, in combination, a work feeding wheel and a coöperating roll both rotatable about approximately parallel axes and constructed and arranged to engage directly opposite portions of the sides of a sole incorporated in a shoe at and adjacent the sole edge and mechanisms for rotating both wheel and roll in the same direction and at different peripheral speeds.
2. A machine of the class described having, in combination, a work feeding wheel, a spirally ribbed channel closing roll coöperating therewith, the wheel and roll being rotatable about substantially horizontal axes and being constructed and arranged to engage opposite sides of the margin of the sole of a shoe, mechanism for rotating the wheel and mechanism for rotating the roll at a peripheral speed many times greater than that of the wheel.
3. A machine of the class described having, in combination, a frusto-conical work feeding wheel and a frusto-conical spirally ribbed work supporting roll, both being mounted on substantially horizontal axes with their bases oppositely directed and being constructed and arranged to engage opposite sides of the margin of a sole, together with mechanisms for rotating the wheel and roll at substantially different speeds.
4. A machine of the class described having, in combination, a work feeding wheel and a coöperating roll constructed and arranged to engage opposite sides of the margin of the sole of a shoe and vibrating pounding tools constructed and arranged to act respectively upon the upper and upon the edge of the sole.
5. A machine of the class described having, in combination, a roll provided with means for closing the channel of the sole of a shoe, a coöperating vibrating tool for pounding the edge of the sole, means for rotating the roll continuously at a relatively high speed and means for actuating the pounding tool simultaneously in a direction approximately parallel to the tread face of the sole to impart a rapid succession of blows to the edge of the sole.
6. A machine of the class described having, in combination, a channel closing roll and a coöperating vibrating tool for pounding the edge of the sole of a shoe, means for rotating the roll at a high speed and means, including a spring, for simultaneously actuating the tool to impart a rapid succession of yielding blows to the edge of the sole.
7. A machine of the class described having, in combination, vibrating pounding tools having substantially parallel pound-
- ing faces constructed and arranged to act respectively upon the upper of a shoe and upon the edge of the sole, a single actuating lever and connections therefrom to each of said tools, said tools being relatively movable toward and from each other.
8. A machine of the class described having, in combination, vibrating pounding tools constructed and arranged to act respectively upon the upper of a shoe and upon the edge of the sole, a single actuating lever and connections therefrom to each of said tools, each set of connections including provision for lost motion or play between the lever and the tool, and mechanism for feeding the shoe including a roll provided with means for closing the channel of the sole.
9. A machine of the class described having, in combination, a support for the tread face of the sole of a shoe, a work feeding wheel constructed and arranged to engage the feather or opposite face of the sole, and a vibrating tool for pounding the upper of the shoe.
10. A machine of the class described having, in combination, a hollow work feeding wheel and a work supporting roll constructed and arranged to engage opposite sides of the margin of the sole of a shoe and a reciprocating spindle concentrically mounted within the feed wheel and provided at its outer end with a tool for pounding the upper of the shoe.
11. A machine of the class described having, in combination, a hollow work feeding wheel and a coöperating work supporting roll constructed and arranged to engage opposite sides of the margin of the sole of a shoe and to bend said margin away from the upper of the shoe, an upper pounding tool reciprocable within the hollow feed wheel, a sole edge pounding tool and mechanism for vibrating both pounding tools simultaneously as the work is progressively fed past them.
12. A machine of the class described having, in combination, a frusto-conical spirally ribbed channel closing roll, the surface of which moves in the general direction of the channel, and a frusto-conical work feeding wheel, said roll and wheel engaging opposite sides of the margin of the sole of a shoe and the larger ends of the roll and wheel being oppositely directed, together with mechanisms for rotating wheel and roll at substantially different speeds.
13. A machine of the class described having, in combination, a work feeding wheel and a roll provided with means for closing the channel of the sole of a shoe, said wheel and roll being constructed and arranged to engage opposite sides of the margin of the sole and also being movable relatively to

- ward and from each other, mechanism for rotating said wheel and roll at substantially different speeds and a separate edge pounding tool maintained constantly in the same position relatively to the channel closing roll notwithstanding variations in the thickness of the sole.

In testimony whereof I have signed my name to this specification in the presence of two subscribing witnesses.
